UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

DESIGN FOR A PADLOCK-CASE.

SPECIFICATION forming part of Design No. 24,930, dated November 26, 1895.

Application filed October 12, 1895. Serial No. 565,521. Term of patent 14 years.

To all whom it may concern:

Be it known that I, WARREN H. TAYLOR, a citizen of the United States, and a resident of Stamford, in the county of Fairfield and 5 State of Connecticut, have invented and produced a new and original Design for a Padlock-Case, of which the following is a specification, reference being had to the accompanying drawings, forming a part thereof.

Figure 1 is a front elevation of a padlock-case, showing my design. Fig. 2 is an end elevation of the same. Fig. 3 is a front elevation of the padlock-case, showing the utility of the circular boss, which provides a panel 15 for a trefoil figure, which in turn provides a panel for any desired lettering. The dotted lines indicate the shackle by which the case is supported.

The leading features of my design consist 20 in the T-shaped raised portion at the front of the case having a circular boss on the face

thereof, the T-shaped raised portion at the back of the case having a circular boss, and the T-shaped raised portion at the ends.

My design is in the form of a parallelopipedon body, which constitutes the case of a padlock. At the front, back, and ends of the body are horizontal and vertical raised portions providing T-shaped figures, and located on the faces of the front and back T-shaped figures are circular bosses providing panels which may contain a trefoil figure, within which may be any lettering desired. 25 30

Having thus described my invention, the following is what I claim as new therein and 35 desire to secure by Design Letters Patent:

The design for a padlock-case; substantially as herein shown and described.

WARREN H. TAYLOR.
